UNITED STATES PATENT OFFICE

168,125

ADVERTISING DISPLAY STANDARD

Lloyd A. Sauer, Milwaukee, Wis.

Application August 18, 1952, Serial No. 21,090

Term of patent 7 years

(Cl. D1—12)

To all whom it may concern:

Be it known that I, Lloyd A. Sauer, a citizen of the United States of America, residing at Milwaukee, in the county of Milwaukee and State of Wisconsin, have invented a new, original, and ornamental Design for an Advertising Display Standard, of which the following is a specification, reference being had to the accompanying drawing, forming a part thereof.

Figure 1 is a front elevational view of an advertising display standard showing my new design.

Fig. 2 is an edge elevational view.

Fig. 3 is a plan view.

I claim:

The ornamental design for an advertising display standard, as shown.

LLOYD A. SAUER.
